(57) **CLAIM**

The ornamental design for a handleset for a latch mechanism, substantially as shown and described.

DESCRIPTION

FIG. 1 is an upper front isometric view of a handleset for latch mechanism;

FIG. 2 is a front elevation view of the handleset for a latch mechanism shown in use;

FIG. 3 is a rear elevation view thereof;

FIG. 4 is a left side elevation view thereof;

FIG. 5 is a right side elevation view thereof;

FIG. 6 is an upper right isometric view thereof; and,

FIG. 7 is a lower left isometric view thereof.

The broken lines in the figures illustrate environmental structures that form no part of the claimed design.
